[45] Date of Patent: ** Aug. 10, 1993

[54] V-GROVE SANDING PLATE

4,780,991 11/1988 Gosis 51/131.3

[76] Inventor: Carl A. Kaylor, 3940 Claremont PL,
Weirton, W. Va. 26062

Primary Examiner—Alan P. Douglas

Assistant Examiner—Antoine D. Davis

Attorney, Agent, or Firm—Terry M. Gernstein

[**] Term: 14 Years

[57] CLAIM

[21] Appl. No.: 806,465

The ornamental design for a v-grove sanding plate, as
shown and described.

[22] Filed: Dec. 13, 1991

DESCRIPTION

[52] U.S. Cl. D15/126

FIG. 1 is a perspective view of the v-grove sanding
plate embodying the design of the present invention;
FIG. 2 is a front end elevational view thereof, the rear
end being a mirror image of the front shown in FIG. 2;
FIG. 3 is a side elevational view thereof;
FIG. 4 is a side elevational view thereof;
FIG. 5 is a top plan view thereof; and,
FIG. 6 is a bottom view thereof.
